2,578,064

CONTRACTILE REEL FOR PAPER CUTTING MACHINES

John M. Hammond, Glendale, Calif., assignor to
Herman J. Minkus, Los Angeles, Calif.

Application January 5, 1948, Serial No. 489

3 Claims. (Cl. 242—111)

1

This invention relates to machine for cutting material such as paper and has particular reference to means for cutting a web of the material into sheets of predetermined uniform lengths.

In devices of the type referred to, a web of paper or the like is fed from a roll of material to a reel which is manually rotatable step by step uniformly to advance the web from the roller into the line of travel of a cutting element.

It is the object of the present invention to provide improved means for so advancing a web of paper to a reel. It is a further object to provide improved means for imparting step by step rotation to said reel. Another object is to provide improved means for adjusting the size of this reel. A still further object is to provide additional means for very fine adjustment of the reel to overcome and rectify slight inaccuracies in the initial adjustment thereof.

These objects and the many advantageous novel features of the invention will become apparent upon perusal of the following detailed description and reference is invited to the accompanying drawings in which preferred forms of the invention are illustrated.

In the drawings:

Fig. 1 is a front elevational view of a paper cutting machine embodying the invention;

Fig. 2 is an end view of the machine taken in the direction of the arrow 2 of Fig. 1;

Fig. 3 is a cross-sectional end view taken substantially on line 3—3 of Fig. 1, in the direction of the arrow 3;

Fig. 4 is a cross-sectional end view of the machine taken on line 4—4 of Fig. 1 in the direction of the arrow 4;

Fig. 5 is a fragmentary view of a portion of the left end of Fig. 1, taken in the direction of the arrow 5 thereof;

Fig. 6 is a detail view, in the direction of the arrow 6 in Fig. 3, of certain important adjusting mechanism thereof which is hereinafter fully described;

Fig. 7 is a fragmentary view of the paper cutting mechanism of the machine; and

Fig. 8 is a detail view, on line 8—8 in Fig. 3, of another portion of the machine, the importance of which is hereinafter fully explained.

The device illustrated in the drawings includes a base 1 on which are mounted end frames 2, 3 and a shaft 4 is hung for rotation in these frames. This shaft is, in a manner which will be described presently, connected for rotation by a hand lever 5. On the shaft is mounted a pair of frames 6, which are connected to support a

2

plurality of bars 8 parallel with and in spaced relation to the axis of the shaft. The frames 6 may be exactly alike and description of one pertains, for this reason, equally to the other. The bars 8 also may be identical and description thereof is, for this reason, limited to one of the bars. Each frame 6 is stelliform, including a hub from which extend three radially directed equidistantly spaced arms 7. These arms are shaped to receive links 9, which latter are pivotally mounted on the bar 8 as indicated at 10, 11.

A rod 15 extends through the frame 6 and it is noticed that this rod is provided with right and left screw threads engaging threaded perforations of the frames. A hub 16 is secured to this rod intermediate the frames and it is made with sockets 16^a for receiving a tool by means of which rotation is imparted to the hub and the rod thereby to move the frames axially on the rod 15. A grooved sleeve 17 is secured to the shaft 4 and it is noticed that the groove of this sleeve is engaged by the hub 16, of the rod to maintain the latter axially in fixed position relative to the shaft during the adjustment of the frames. It is furthermore to be noted that the axial adjustment of the frames is by the links 9 translated into a radial movement of the bars 8 and it is important to note that the bars are during this radial movement, rigidly held against movement lengthwise thereof. This finely adjusted and rigidly held frame construction forms the most important feature of the invention.

The end frames 2, 3 are shown grooved at the top to receive a shaft 20 to which are secured a pair of shouldered sleeves 21 for lengthwise adjustment thereon. These sleeves are designed to receive a roll of paper 22 or other material to be cut and the web 22^a is extended over a roller 23 and then folded over the bars 8 substantially as indicated in Fig. 3.

It is now noticed that rows of pins 24 project radially from the outer surfaces of the bars for the purpose of maintaining the web of material in position thereon during the operation of the machine. The bar assembly on the shaft 4 is hereinafter, for convenience, referred to as the reel of the machine. It is also to be noted that the roller 23 is provided with grooves 23^a in line with the pins 24 and that these grooves are deep enough to permit the pins freely to pass therethrough during rotations of the reel.

The mechanism by means of which the reel is rotated, includes an arm 25, forming the inner end of the lever 5, is seated and this arm is rotatably secured to a stub shaft 26 which extends

through the side frame 3 and is within the frame fitted with a relatively large gear wheel 27 in mesh with the gear pinion 28 of the shaft 4. To the stub shaft 26 is rigidly secured a ratchet wheel 26^a and a pawl 26^b is hung on the arm 25 in position to engage and rotate the ratchet wheel and shaft each time the arm 25 is swung downward. A relatively slow movement of the arm 25 is, in this manner, translated into a faster movement of the reel shaft.

A disk 30 is secured to the outer end of the shaft 4 and it is made with a series of radial projections 31 corresponding in number to the bars of the reel and equidistantly spaced about the periphery of the disk. A lever 32 is pivotally mounted on the side frame 3, at 33, and it is provided with a shoulder 32^a which is engaged by one of the projections 31 to bring the reel to a stop in correct position at the end of each rotation thereof. A spring 34 urges this stop into position of engagement by the projection of the disc. A plate 36 is pivotally hung on the side frame 3 in front of the disk 30 and this plate is made with a perforation 36^a within which a stud 31 of the arm 25 is mounted to ride thereby to control the extent of movement of the arm. It is important to note that the perforation of this plate is so shaped that the plate is caused to swing on its pivot into the position shown in dotted line in Fig. 2 at the end of each reciprocating movement of the arm 25. It is also important to note that when the plate is moved into the elevated position shown in dotted outline, it engages the front end of the lever 32 thereby to swing this lever on its pivot sufficiently to disengage the stop 32^a from the projection 31 of the disc against the tension of the spring 34. Oscillating movement of the lever is controlled and limited by a stud 39 of the end frame seated in an elongated perforation 32^c of the lever. As shown in Figs. 1 and 5, a sleeve 40 is made with an extension 40^a and a stud 41 of the side frame 2 engages a perforation of this extension to lock the sleeve against rotation with the shaft 4. The portion of the sleeve opposite the extension 40^a is shown slotted and a screw 42 extends through this slotted portion for the purpose of drawing the sleeve tightly about the shaft thereby to provide sufficient friction to maintain the shaft in the position it attains at the end of each hand lever operation.

The arm 25 is urged into elevated position by a spring 43 engaging a collar 44 of a rod 45, the upper end of which is seated in a perforation 25^a of the arm and it is noticed that the upward movement of the arm is limited by the plate 36 contacting the end 32^b of the lever 32. As the arm is manually lowered to rotate the reel, it is found that the bar 8 at the front of the machine is caused to move upward and to pass directly under the roller 23 during which movement the pins 24 of the bar are caused to penetrate the web of material and so to maintain this web in correct relation to the reel during the operation of the machine. As above stated and as best shown in Fig. 1, the roller 23 is provided with a series of grooves 23^a in alignment with the pins 24 and these grooves are deep enough to permit the pins freely to pass through the grooves of the roller. A bar 46 is secured to rods 47 which are seated for axial adjustment within lugs 48 of the side frames and this bar is, as indicated in Fig. 3, positioned directly in front of the bar 8 to form a guard for protection of the operator's hands.

Plate 50 is fitted with lugs 51 which are mounted for axial adjustment on rods 52 and the inner ends of the latter are rigidly seated in lugs 53 of the end plates. The rods 52 and plate 50 are, as best shown in Fig. 3, set at an angle parallel with a radial line through the pins 24 of the adjacent bar 8 a short distance below these pins. A knife 54 is placed on this plate and it is pivotally secured to one end thereof as indicated at 55. A stud 56 is secured to and freely rotatable relative to the knife and this stud is perforated to receive a rod 57, the inner end of which is bent downward to ride in the perforation of an arm 58. The latter is mounted for rotation on and projects forward from a lug 59 of the end plate.

A pawl 60 is pivotally hung on the arm 25 as indicated at 61 and it is perforated at 60^a to ride on a stud 62 of the end frame. This pawl is made with a stop shoulder 60^b which, while the operating handle is in elevated position, takes a position in front of the arm 58 but it is to be noted that the pawl during the downward movement of the operating handle passes under this arm causing the stop shoulder 60^b to take a position behind and to clear the arm whereupon a spring 63 swings the pawl upward into the position shown in Fig. 2 of engagement with the arm. When thereupon, the hand lever is returned to its elevated position, it is found that the arm is by its stop 60^b swung on its pivot to draw the knife 54 past the underside of the pins 24, thereby to sever the web of material at this point. Attention is, at this time, directed to a slot 8^a which is recessed into the bar 8 in the line of movement of the knife and which is provided for the purpose of affording the knife of freedom of movement without danger of colliding with the bar. The slot 60^a of the pawl is so shaped as to cause the stop 60^b to move downward during the return movement of the operating lever sufficiently to clear the arm 58 and so to permit a spring 65 of the knife to return the knife and the arm to their original positions. The end of the web which has been severed from the body portion thereof, swings by gravity downward to the position indicated at 22^b in Fig. 3, in which it is held by the pins of the bar 8 at the front of the machine in position to be manually removed by the operator.

As above stated, the frames of the reel are axially movable to increase or decrease the size thereof to correspond to the size of the material to be cut and it is to be noted that it becomes necessary to move the roller 23 correspondingly. The roller is for this purpose, in Figs. 1 and 8, shown seated for rotation within bosses 57 which are secured to the end walls by means of screws 66 and the latter extend through vertically directed slots of the end frames for vertical adjustment of the roller therein. It is important to note that the plate 50 is mounted for axial adjustment on the rods 52 in order correctly to adjust the position thereof in relation to the bars 8 to correspond with the adjustment of the reel and of the roller 23.

The roll of material to be cut on the machine often carries advertising matter printed thereon and while such printed matter is equidistantly spaced on the material, it may sometimes be found difficult during the operation of the machine to maintain the cut in correct relation to the sheets. Correction may, of course, be made by rotation of the rod 15 to adjust the size of the reel but such adjustment is not only laborious

but it may be found rather difficult to obtain a very fine adjustment for this purpose. In order to simplify such adjustment and so as to be able to maintain the machine in operation without serious delays, I have, as indicated in Fig. 6, shown a gauging strip 70 placed on one of the bars 8. The strip is fastened to the bar by means of screws or studs 71 which ride in cam-shaped perforations 70^a of the strip and these perforations are shaped to advance the strip radially relative to the bar when it is lengthwise moved thereon sufficiently slightly to increase the size of the reel as may be required for adjustment thereof relative to the length of web to be cut. The strip is, for the purpose of facilitating lengthwise movement thereon at one end bent to form a lip 72^b and the latter is conveniently placed for engagement by the fingers of the operator.

The roll of material should be held under slight pressure during the operation of the machine and a brake drum 73 is for this purpose secured to one end of the shaft 20. A lever 74 is pivotally hung on the end frame 3 adjacent this brake drum. The lever is shown fitted with a brake shoe 75 contacting the periphery of the drum and a screw 76 is seated in threads at the opposite end of the lever for engagement with a stop of the end plate. Adjustment of this screw serves to apply friction to the brake drum as may be required for the proper operation of the machine, and it is locked in adjusted position by means of a wing nut 77.

It is seen from the foregoing description that I have provided improved means for adjustably supporting and rigidly maintaining the pin bars of the device in adjusted position on the machine. It is also important to note that the reel rotating mechanism is designed to advance the reel with great precision so as to cause the end of the web to be correctly positioned relative to the knife. Also that sufficient friction is applied to the roll of material to maintain the web taut at all times.

Another important feature is the means for fine adjustment of the size of the reel by movement of the plate 70 on one of the bars 8 thereof. But while I have described a preferred form of the invention, I may embody modifications of the various features thereof within the scope of the claims hereto appended.

I claim:

1. In a device for cutting the web from a roll of material into sheets of predetermined uniform length, a shaft, a reel on said shaft including a series of equidistant bars in parallel relation to the shaft, means for imparting step by step movement to the shaft and reel, means for uniformly adjusting the bars of said reel radially relative to

the shaft, vertically disposed guides, a roller mounted in said guides for vertical adjustment therein to position the roller adjacent the path of travel of said bars, the web of material from 5 said material roll being bent over said roller and over the said bars, pins radially projecting from the bars, and grooves in said roller in alignment with said pins providing clearance for free passage of the pins therethrough, the pins penetrating the web as they pass through said grooves thereby to retain the web in position on the reel.

2. In a device for cutting the web from a roll of material into sheets of predetermined uniform length, a shaft, a reel on said shaft including a series of equidistant bars in parallel relation to the shaft, means for imparting step by step movement to the shaft and reel, means for uniformly adjusting the bars of said reel radially relative to the shaft, and means movable on one of said bars 15 to project beyond the peripheral surface thereof for very fine adjustment of the reel to correct inaccuracies in the initial adjustment thereof.

3. In a device for cutting the web from a roll of material into sheets of predetermined uniform length, a shaft, a reel on said shaft including a series of equidistant bars in parallel relation to the shaft, means for imparting step by step movement to the shaft and reel, means for uniformly adjusting the bars of said reel radially relative to the shaft, studs on one side of one of said bars, and a strip of material having cam slots therein receiving said studs, the strip being lengthwise movable on said studs along the bar to cause the outer edge thereof slightly to project beyond the 30 peripheral surface of the bar thereby to provide 35 more perfect adjustment of the reel.

JOHN M. HAMMOND.
